(57) **CLAIM**

The ornamental design for a chair, as shown and described.

DESCRIPTION

FIG. 1 is a perspective view of a chair showing our new design;

FIG. 2 is a front view thereof;

FIG. 3 is a rear view thereof;

FIG. 4 is a right side view thereof;

FIG. 5 is a left side view thereof;

FIG. 6 a top view thereof; and,

FIG. 7 is a perspective view thereof in another configuration.

The broken lines in FIG. 7 are for the purpose of illustrating the environmental structures and form no part of the claimed design.
